UNITED STATES PATENT OFFICE.

BENJAMIN FRANKLIN OREWILER, OF CHICAGO, ILLINOIS, ASSIGNOR TO KABO CORSET CO., OF CHICAGO, ILLINOIS, A CORPORATION OF WEST VIRGINIA.

BRASSIÈRE-BUCKLE.

1,267,895.

Specification of Letters Patent. Patented May 28, 1918.

Application filed August 18, 1917. Serial No. 186,904.

To all whom it may concern:

Be it known that I, BENJAMIN F. OREWILER, a citizen of the United States, residing at Chicago, in the county of Cook and 5 State of Illinois, have invented certain new and useful Improvements in Brassière-Buckles, of which the following is a specification.

The present invention relates to a hook or 10 buckle attached to the end of a suspending strap, which in turn is secured to the lower edge of a brassière. The buckle of the present invention is for the purpose of connecting the brassière to the corset, and is an improvement on the construction shown and 15 described in Letters Patent of the United States No. 1,200,518, granted to me October 10, 1916, for brassière buckles.

One of the objects of the present invention is to so configure the buckle as to enable 20 it to be used with either a front-lace or a back-lace corset.

Another object of the invention is to impart to the buckle a certain amount of resiliency in order that it may accommodate 25 stud shanks of different diameters.

A further object of the invention is to so configure the buckle as to enable it to easily and quickly expand and contract, thereby 30 enabling an easy placing and removal with respect to the stud shank.

A further object of the invention is to provide a buckle of the kind specified, which is simple and cheap of construction and 35 capable of use under all ordinary conditions.

The invention further consists in the features of construction and combination of parts hereinafter described and claimed.

In the drawings:

40 Figure 1 is an elevation showing a portion of a back-lace corset with the buckle of the present invention applied thereto;

Fig. 2, an elevation showing a portion of a front-lace corset with the buckle of the 45 present invention applied thereto;

Fig. 3, a front view of the buckle detached;

Fig. 4, a rear view of the buckle, showing by means of dotted lines the buckle spread 50 to allow the insertion of stud shanks of relatively large diameter; and

Fig. 5, a detail section on line 5—5 of Fig. 4, looking in the direction of the arrows.

55 In the art to which the present invention

relates, in connection with an article of clothing known as a brassière, there is utilized a hook or buckle for the purpose of connecting the brassière to the corset, thereby holding the former in the stretched condition desired. These hooks are now made in a manner to enable them to engage with the stud shanks of back-lace corsets and the lacings of front-lace corsets. The stud shanks will vary somewhat in diameter, and 60 difficulty has been experienced in the use of such buckles with respect to their holding power on stud shanks of different diameters. When made for shanks of maximum diameter, a shank of smaller diameter will be 65 loosely engaged by the buckle, with the result that the buckle and stud will become separated. If made for a shank of small diameter, the larger sized shanks will be too great in diameter to fit in the slot of the 70 buckle and, therefore, the buckle cannot be attached to the shank.

In my prior Patent, No. 1,200,518, above referred to, a design of buckle is shown which, by means of certain slots, was intended to give resiliency enough to allow for the use of various sized shanks, but difficulty was found with this construction, in that it was impractical to use it with large sized shanks, owing to the stiffness of the spring 85 action.

The present invention is an improvement of the construction set forth in my patent above referred to and is intended to eliminate the objection of stiffness in applying 90 the buckle to the stud shank, and at the same time enable shanks of different diameters to be securely attached to the buckle.

Referring now to the drawings, the style of buckle shown is formed from a single 95 piece of spring sheet-metal 6. One end of the blank from which the buckle is formed is of reduced width from the other, as will be apparent from the drawings. The end which is of reduced width is bent back upon the remainder of the body to form a hook 7. The forming of this hook creates what may be termed a back portion 8 of the body and a top portion 9.

Formed adjacent the inner end of the 105 back portion 8 are transverse slots 10 extending substantially across that end of the body, and these slots are intended to receive one end of a suspending strap 11 connected to the lower end of the brassière. 110

By forming the slots 10 so that they extend substantially the entire distance across the body, a relatively narrow web 12 is left between the ends of these slots and the edges 5 of the buckle body.

Communicating with the lowermost of the slots 10, approximately midway between its ends, is a cross slot 13 which merges into a longitudinal slot 14 of key-hole formation. Midway the ends of the slot 14 is formed a restricted portion 15 produced by two oppositely disposed, inwardly projecting, rounded shoulders 16. The slot 14 in turn communicates with a slot 17 which extends to a point adjacent the end of the top portion 9. By this arrangement there is formed a continuous slot in said buckle composed of the lower slot 10 and the slots 13, 14 and 17. This 10 gives a very openwork construction to the buckle, and the walls of the slot 14 can give freely and easily, working only against the tension of the narrow webs 12 between the ends of the slot 10 and the edges of the 15 body of the buckle.

This openwork construction has to do with the operation of the buckle when used in conjunction with back-lace corsets, in which case the buckle is secured to the 20 shank of the stud forming a portion of the connection at the front of the corset.

The shanks 18 of these studs 19 will vary in diameter and, accordingly, there must be a spring action on the part of the buckle 25 in order that the slot in the buckle may accommodate studs having shanks of different diameters. In applying the buckle to a stud shank, the head of the stud is inserted through the enlarged portion of the slot 40 14, and the buckle is then drawn so that the shank passes by the shoulders 16. These shoulders are made slightly closer together than the diameter of the smallest sized stud shank, and when the shank is drawn by 45 these shoulders, the walls of the slot 14 will be spread apart. The spreading action will be very easy, because it is only against the tension of the narrow strip of metal 12, and the shoulders 16 being at some distance 50 from the said strips 12, there will be a considerable leverage action, causing an easy and free spreading of the walls of the slot.

After passing by said restriction, the shank of the stud rests within the enlarged 55 portion of the slot beyond the restriction

and designated by the numeral 20. When the shank passes into the portion 20 of the slot 14, the walls of the slot will contract into normal position and the shoulder 16 will close up behind the shank, thus holding the shank against accidental removal from the slot. The head of the stud will lie beneath the top portion 9 of the buckle. By giving this resiliency to the body of the buckle, its application to various sizes of 60 stud shanks is easy and the shanks will be held by the buckle in a manner to prevent accidental disconnection between the buckle and shanks.

The formation of the hook 7 is for the 70 purpose of allowing the buckle to be connected to the lacing cords of a front-lace corset, as shown in Fig. 2.

In connection with the passage of the shank by the shoulders 16, the pull exerted 75 by the user in drawing the buckle into place will have a tendency to cause the walls of said slot to have a slight transverse movement with respect to one another, as well as a spreading movement. This action is 80 shown in the enlarged detail of Fig. 5 and assists in allowing the shank to easily pass by the restriction. The buckle body formed as described therefore possesses a flexibility allowing a movement of the walls of the 85 slot 14 both away from one another and transversely of one another.

I claim:

A brassière buckle formed of a body consisting of a single piece of spring-metal 90 bent at one end to form a hook, the opposite end being formed with a transverse slot extending substantially thereacross to receive a suspending strap, said slot extending close to the side edges of the body 95 to form a thin web at such points, said body being further formed with a longitudinal slot extending from said transverse slot to adjacent the end of the hook, said longitudinal slot for that portion lying beneath the hook being formed to receive a stud shank, and the walls of said slot expanding when the shank is inserted against the tension of the thin webs beyond the 100 ends of the transverse slot, whereby the walls of said longitudinal slot may freely expand and contract for the purpose of accommodating stud shanks of different diameters, substantially as described.

BENJAMIN FRANKLIN OREWILER.
